(57) **CLAIM**

The ornamental design for a raceway cover, as shown and
described.

DESCRIPTION

FIG. 1 is a top right front perspective view of a raceway
cover showing our new design;

FIG. 2 is a front view, with the rear view a mirror image
thereof;

FIG. 3 is a left side view, with the right side view a mirror
image thereof; and,

FIG. 4 is a top view thereof.

The broken line showing of the latching mechanism in
FIGS. 1, 2 and 3 is for illustrative purposes only and forms
no part of the claimed design.
